His Attorney

UNITED STATES PATENT OFFICE.

CONRAD H. ZIERDT, OF ROSEDALE, PENN TOWNSHIP, ALLEGHENY COUNTY, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed April 2, 1924. Serial No. 703,681.

To all whom it may concern:

Be it known that I, CONRAD H. ZIERDT, a citizen of the United States, residing at Rosedale, Penn Township, in the county of Allegheny and State of Pennsylvania, have invented certain new and useful Improvements in Railway-Traffic-Controlling Apparatus, of which the following is a specification.

- 10 My invention relates to railway traffic controlling apparatus, and particularly to apparatus of the type comprising means responsive to currents flowing in the trackway for controlling traffic. More particularly 15 my present invention relates to the trackway portion of such apparatus.

I will describe two forms of railway traffic controlling apparatus embodying my invention, and will then point out the novel 20 features thereof in claims.

In the accompanying drawing, Fig. 1 is a diagrammatic view showing one form and arrangement of trackway circuit embodying my invention. Fig. 2 is a view showing 25 a modification of the apparatus illustrated in Fig. 1 and also embodying my invention.

Similar reference characters refer to similar parts in both views.

Referring first to Fig. 1, the reference 30 characters 1 and 1^a designate the track rails of a stretch of railway track. These rails are divided, by means of insulated joints 2, into a plurality of successive sections, of which two adjoining sections A—B and 35 B—C are here shown.

Each section is provided with a track transformer designated by the reference character T with a suitable exponent and having its secondary winding 3 connected 40 across the rails adjacent the left hand end of the section. An impedance 5 is interposed between the secondary 3 of each track transformer T and one rail 1^a of the associated section in the usual manner. The 45 primary winding 4 of each track transformer is constantly supplied with alternating current from a source not shown in the drawing.

Each section is also provided with a 50 transformer which I will term a "protecting" transformer and which is designated by the reference character D with a suitable exponent. The primary 7 of each pro-

tecting transformer D is constantly connected across the rails adjacent the right 55 hand end of the corresponding section.

Each section is further provided with a track relay designated by the reference character R with a distinguishing exponent, which relay is connected with the secondary 60 8 of the protecting transformer for the same section.

The track relays R may be used to control suitable apparatus, not shown in the drawing, in any desired manner. 65

Means are also provided for supplying the rails of each section in parallel with a current which I shall hereinafter term a "loop" current. For this purpose I provide an impedance 6 connected across the rails adjacent the left hand end of each section. The immediate supply of loop current to each section is a loop transformer local to such section and here designated by the reference character J with a suitable distinguished exponent. The primary 9 of each such loop transformer is supplied with alternating current from some suitable source not shown in the drawing. Referring particularly to transformer J^A, the left hand terminal of 70 the secondary 10 of this transformer is connected with the mid point of impedance 6 in section A—B, and the right hand terminal of this secondary is connected with the mid point a of primary 7 of transformer 75 D^B. A resistance 30 is interposed between the secondary 10 of transformer J^A and the primary transformer D^B one function of which is to regulate the amount of current 80 flowing through the loop circuit. It will thus be clear that each section is provided with a loop circuit including the secondary 85 10 of a loop transformer, the oppositely connected halves of the associated impedance 6 in parallel, the rails 1 and 1^a of the associated section in parallel, a resistance 30 and the two halves of the primary 7 of a protecting transformer D. It will be observed however, that loop current flows in 90 opposite directions through the two halves 95 of the primary of the protecting transformer D and hence has no effect upon the track relay R associated therewith.

If, however, a break occurs in one rail of a section, all the loop current will flow 105 through one half of the primary of the

protecting transformer. For example I will assume that a break occurs in rail 1 of section A—B. All the loop current will then flow through the right hand half of 5 primary 7 of transformer D^B. The impedance offered to loop current by this winding is a comparatively small part of the total impedance of the loop circuit, and the transformer D^B acts as a current transformer to 10 loop current. The ratio of transformer D^B for this unbalanced loop current is however only one half of the ratio of this transformer for track circuit current since only half the turns of the primary 7 are then included in the loop circuit. The current 15 flowing through relay R^B due to the loop current in primary 7 will therefore be only a fraction of the total loop current in winding 7, and the parts are so proportioned that 20 relay R^B will not be picked up or held in its energized condition by a current of this reduced value. As shown in the drawing the transformer D^B has the same number of turns in primary 7 as in secondary 8, but 25 this particular construction is not essential.

The track currents may be used to control traffic governing means in any desired manner.

Referring now to Fig. 2, the single section 30 A—B here shown is connected with adjacent sections by impedance bonds designated by the reference character K with suitable distinguishing exponents. Each impedance bond K is of the usual form comprising two 35 impedances 12 and 13 connected across the rails of the adjoining sections, the mid points of such impedances being connected together by means of a conductor 14. These 40 impedance bonds serve to conduct propulsion current past the insulated joints 2 in the usual and well known manner.

The track circuit for section A—B in Fig. 2 is the same as in Fig. 1, and the loop circuit is also the same as in Fig. 1, except 45 that the left hand terminal of secondary 10 of transformer J^A is connected with the conductor 14 of impedance bond K^A. The operation of the apparatus shown in Fig. 2 is the same as that of the apparatus shown 50 in Fig. 1 and will be readily understood without further explanation.

One advantage of my invention is that the track relay can not be picked up or held in its energized condition by loop current 55 as a result of a broken rail.

Although I have herein shown and described only two forms of trackway apparatus embodying my invention, it is understood that various changes and modifications may be made therein within the scope of the appended claims without departing from the spirit and scope of my invention.

Having thus described my invention, what 60 I claim is:

1. In combination, a stretch of railway track, a source of alternating track circuit current connected across the rails of the stretch, a transformer having a primary winding connected across the rails of the 70 stretch, a track relay connected with the secondary of said transformer, an impedance connected across the rails of said stretch, and a source of train governing loop current having one terminal connected 75 with said impedance and the other terminal connected with an intermediate point in said primary winding, the parts being so proportioned that if a track rail breaks so that all of the loop current flows through one section of said primary winding the current induced thereby in the secondary winding will not be of sufficient value to operate said track relay.

2. In combination, a stretch of railway 80 track, a source of alternating track circuit current connected across the rails of the stretch, a transformer having a primary winding connected across the rails of the stretch, a track relay connected with the 85 secondary of said transformer, an impedance connected across the rails of said stretch, and a source of train governing loop current having one terminal connected 90 with said impedance and the other terminal connected with the mid point of said primary winding, the parts being so proportioned that if a track rail breaks so that all of the loop current flows through half of said primary winding the current 95 induced thereby in said secondary winding will not be of sufficient value to operate said track relay.

3. In combination, a plurality of successive sections of railway track, a source of 100 track circuit current for each section connected across the rails thereof; a transformer for each section having a primary winding connected across the rails of the associated section, a track relay for each 105 section connected with the secondary of the corresponding transformer, an impedance for each section connected across the rails of the associated section, and a separate source of train governing loop current for 110 each section local to such section and having one terminal connected with the corresponding impedance and having the remaining terminal connected with an intermediate point in the primary winding of the 115 associated transformer, the parts being so proportioned that if a track rail in a section breaks so that all of the loop current for such section flows through one portion of the primary winding of the associated transformer the current induced thereby in the secondary winding of such transformer will not be of sufficient value to operate the 120 associated track relay.

4. In combination, a stretch of railway 125

- track having electric propulsion current flowing in the rails thereof, means for insulating a section of track from the remainder of said stretch, impedance bonds for 5 conducting propulsion current past said means, a source of alternating track circuit current connected across the rails of said section, a transformer having a primary winding connected across the rails of 10 said section, a relay connected with the secondary winding of said transformer, and a source of train governing loop current local to said section and having one terminal connected with an intermediate point 15 in said primary winding and the other terminal connected with one of said impedance bonds, the parts being so proportioned that if a track rail breaks so that all of the loop current flows through one section of said 20 primary winding the current induced thereby in the secondary winding will not be of sufficient value to operate said track relay.
5. In combination, a stretch of railway track, a transformer having one winding comprising two portions and connected across the rails of said stretch, means for supplying to said stretch a train controlling current which flows in opposite directions in said two portions at any instant, and a 25 relay connected with a second winding of said transformer, the parts being so proportioned that if a track rail breaks so that all of the train controlling current flows through one portion of the said one transformer winding, the current induced thereby in the second transformer winding will not be of sufficient value to operate said 30 relay.
6. In combination, a stretch of railway track, a source of track circuit current connected across the rails of the stretch, means for supplying train controlling current to the rails of the section in parallel, a track 35 relay, and a transformer for supplying track circuit current from said stretch to said re-
- lay with one transformation ratio and for supplying train controlling current to said relay from said stretch with a different transformation ratio, the parts being so proportioned that when train controlling current is supplied to the relay by the transformer the value of such current is not sufficient to operate the relay. 50
7. In combination, a section of railway track, a source of track circuit current connected across the rails of said stretch, a transformer having a primary winding comprising two portions connected across the rails of said stretch, a loop circuit for said stretch including the two portions of said winding in parallel but oppositely connected, and a track relay connected with the secondary of said transformer, the parts being so proportioned that if a track rail breaks so that all of the loop current passes through one portion of the primary winding the current induced thereby in the secondary will not be of sufficient value to operate the track relay. 55
8. In combination, a section of railway track, a source of alternating track circuit current connected with the rails of said section, a transformer having its primary connected with the rails of said section, a track relay connected with the secondary of said transformer, an impedance connected across the rails of said section, and a loop transformer local to said section and having one terminal connected with an intermediate point in the primary of said transformer and the other terminal connected with said impedance, the parts being so proportioned that if a track rail breaks so that all of the loop current flows through one section of said primary winding the current induced thereby in the secondary winding will not be of sufficient value to operate said track 60 relay. 65

In testimony whereof I affix my signature.

CONRAD H. ZIERDT.
